UNITED STATES PATENT OFFICE.

ROBERT HENDERSON CAMERON, OF TORONTO, ONTARIO, CANADA.

SNOW SKATE.

Application filed April 5, 1926. Serial No. 99,984.

My invention relates to improvements in snow skates, and the object of the invention is to devise a skate capable of being made and sold very cheaply, which can be held 5 very securely on the foot without liability of displacement and which will be rigid, light, strong, safe and durable and which will glide with equal facility on snow and ice.

My invention consists of a foundation bar, 10 a foot plate secured to the bar and provided with spikes, a metal strip secured underneath the bar and curved upwardly at the front into a loop and extending upwardly at the back to form a stop, the said foundation bar having an extension forming a heel stop slotted for a foot strap and the 15 skate being otherwise constructed as herein-after more particularly explained.

Fig. 1 is a perspective view of a snow 20 skate constructed in accordance with my invention.

Fig. 2 is a longitudinal section.

Fig. 3 is a cross section view.

In the drawings like characters of reference indicate corresponding parts in each figure.

1 is the foundation bar of the skate, which is made of a metal strip bent zig-zag in a vertical plane, and having horizontal end 30 portions 1^x and 1°. 2 is a foot plate secured to the foundation bar preferably by spot welding at the upper apex portion of the zig-zag bar and having spikes 4 adjacent the toe portion of the foot plate.

35 6 is a metal strip preferably concaved in cross section which extends from the front to the rear of the foundation bar 1. The metal strip is curved at the front into the form of a loop 6° extending above the plate 40 2 and then down terminating in horizontal extension 6^x passing beneath the toe end of the foot plate. The rear of the strip is curved upward at 6' and inclines inward terminating in a horizontal portion 6² extending beneath the longitudinal rear end 45 of the bar 1.

5 and 5' are toe and heel bolts, the bolt 5 extending through the horizontal end portion 1^x of the bar 1 and the horizontal extension 6^x of the strip 6 and the foot plate 2 securing the parts together at the toe end of the skate, and the bolt 5' through the horizontal end portion 1° of the bar 1 and the horizontal extension 6² of the strip 6, 55 and the foot plate 2 securing the parts together at the heel end of the skate.

7 is a stamped down portion formed in the foot plate forming a slot through which the toe strap 8 extends. The portion 1° of the bar 1 terminates in an upward extension 60 11 forming a heel stop and inwardly and down turned upon itself to form a loop through which the heel strap 10 extends. The heel portion of the foot plate 2 is also provided with upwardly drawn portions 2^x 65 at each side of the heel centre back and forming heel stops.

Having now described the principal parts involved in my invention I shall briefly describe its utility.

The shoe is placed on the foot plate 2, so that the spike 4 extends into the sole, the heel being brought up against the stop 11 and 2^x. The straps 8 and 10 are then tightened around the toe and instep. The 70 loop 6² formed at the front being of metal is more or less resilient and necessarily when it comes in contact with lumps of snow or ice will serve to relieve the jar on the foot of the wearer of the skate, which would not 75 be the case if the front were altogether solid.

As the foundation bar and foot plate are made of light material it will be understood that not only will the skate be rigid but also light and suitable for snow skating, 80 or coasting which is the principal object for which my skate is designed.

What I claim as my invention is:

1. A snow skate comprising a zigzag strip forming a truss like foundation bar, a foot 90 plate secured to the upper apex portions of the foundation bar, a runner strip extending from end to end of the foundation bar and secured to the lower apex portions, and means for securing a shoe to the foot plate. 95

2. A snow skate comprising a zigzag strip forming a truss like foundation bar, a foot plate extending above the foundation bar and secured thereto along its longitudinal centre, and a runner strip located below the foundation bar and extending parallel therewith and secured thereto. 100

3. A snow skate comprising a zigzag strip forming a truss like foundation bar, a foot secured to the upper apex portions of the foundation bar, and a runner strip extending from end to end of the foundation bar and secured to the lower apex portions thereof. 105

ROBERT HENDERSON CAMERON.
